UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

BROACHING ATTACHMENT.

Application filed September 23, 1926. Serial No. 137,301.

This invention relates to rock drills, but more particularly to a broaching attachment for fluid actuated rock drills of the hammer type.

5 The objects of the invention are to enable a broaching tool to be suitably guided during the broaching operation, to facilitate the insertion of the attachment into the tool and the removal therefrom, and to render 10 the attachment capable of accommodating different types of broaching tools.

Other objects will appear hereinafter.

The invention consists of the combination of elements, features of construction, and arrangement of parts substantially as herein-after described and more particularly pointed out in the appended claim and illustrated in the accompanying drawings, in which—

20 Figure 1 is an elevation in section of the front end of a rock drill equipped with a broaching attachment constructed in accordance with the practice of the invention,

25 Figure 2 is a side view of the attachment partly broken away and partly in section illustrating the manner in which the broaching attachment may be secured to the cylinder of the rock drill,

30 Figure 3 is a transverse view taken through Figure 1 on the line 3—3 looking in the direction of the arrows,

Figure 4 is a similar view taken through Figure 2 on the line 4—4,

35 Figure 5 is a view similar to Figure 1 illustrating the manner in which a flat rectangular broaching tool having a rectangular head may be supported by the attachment, and

40 Figure 6 is a view similar to Figures 1 and 5 showing the manner in which a round headed broaching tool is supported by the attachment.

45 Referring to the drawings, the invention is shown embodied in a rock drill in which only a front portion of a cylinder A is shown. Within the cylinder A is a reciprocating hammer piston B adapted to deliver blows to an anvil block C. A front cylinder washer D at the front end of the cylinder forms a closure therefor and also acts as a 50 guide for the anvil block C.

55 The attachment or front head E is supported by the cylinder A and preferably secured thereto by means of bolts F which extend through flanges G and H of the cylinder A and the front cylinder washer D re-

spectively and through an end wall J of the front head E, nuts K being provided for the bolts F for clamping the cylinder and the attachment securely together. In the present instance, the attachment E has an integral 60 side wall L and has end walls O secured to the inner face of the wall L by bolts or screws P, thus leaving one side of the attachment open as at Q.

65 Adjacent that end of the attachment which is secured to the front cylinder washer D is formed a lug R which acts as a bearing for a cover S adapted to lie against the edges of the end walls O and has rearwardly extending arms T which bear against the ends of the lugs R. Apertures U are formed through the lug R and through the arms T for the reception of a pin V which acts as a pivot for the cover S. In this way is formed a closure for the open side 75 Q for the attachment E.

70 Any suitable means may be provided for clamping the cover S securely in operative position. In the present instance I-bolts W pivoted to the wall L extend through slots X in the cover S and in the side walls O and are provided with nuts Y which may be turned against the cover S after said cover has been closed.

75 Disposed on the inner surfaces of the wall 80 L and the cover S are cheek plates Z of preferably the same width as the space between the end walls O. These cheek plates are spaced with respect to each other to form a guideway b therebetween and are preferably secured to the wall L and the cover S by means of bolts c. In order to protect the bolts c against excessive strain caused by 85 occasional impact of the anvil block C against the cheek plates, the cheek plates are 90 provided with transverse keys or tongues d which extend into slots e.

95 The guideway b as formed by the end walls O and the inner surfaces of the cheek plates Z is of rectangular cross sectional area 100 adapted more particularly for accommodating and loosely guiding flat rectangular broaching tools f of the type illustrated in Figure 5. As is well known, there are a variety of broaching tools of different designs particularly with respect to the shank, a few of these types being illustrated in the drawings. The broaching tool g illustrated in Figures 1 to 4 inclusive is of a well known type in which the body portion h is 105 110

- of flat rectangular cross sectional area and the shank of which may be either of hexagonal or cylindrical shape. In order to render the present attachment capable of 5 accommodating tools of this type, longitudinal grooves *k* are formed on the inner surfaces of the cheek plate *Z* for the reception of a shank *o* of the broaching tool *g*. These grooves *k* may extend from the 10 rearward end of the cheek plates to recesses *p* formed near the front ends of the cheek plates and into which recesses may extend a collar *q* carried by the tool *g*. The recesses *p* are of such length as to permit a considerable 15 range of movement in a longitudinal direction of the tool *g* and the ends of the recesses *p* are adapted to cooperate with the collar *q* for limiting the movement of the tool with respect to the cheek plates. 20 Means are also provided on the cheek plates for preventing ejection of the tool *f* illustrated in Figure 5. To this end shoulders *r* are formed across the inner surfaces of the cheek plates *Z* to cooperate with shoulders *s* formed on the rearward end of the 25 tool *f*. In Figure 6 is illustrated a tool *t* having a rectangular body portion and carrying at its rearward end a cylindrical head *u* against 30 which the blows of the anvil block *C* are delivered. In order to prevent ejection of this type of tool from the attachment, arcuate recesses *v* are formed in the rearward end of the cheek plates *Z* and the end walls 35 *w* of these recesses *v* act as stops for the head *u*. In practice whenever it is desired to change 40 broaching tools, the nuts *Y* on the bolts *W* may be partly unscrewed to permit the bolts to be rocked out of the slot *X*. The cover *S* may then be oscillated about its pivot as

illustrated by the dot and dash lines in Figure 1 and the broaching tool may be removed from the attachment. After another tool has been inserted in the attachment the cover *S* 45 may again be clamped to the side of the attachment.

The present invention is not limited in its use to one particular type of broaching tool, but will accommodate broaching tools of 50 different designs. This is particularly desirable in broaching operations in which various types of broaching tools are in use and will eliminate the expense of providing a separate broaching attachment suitable for 55 each particular type of broaching tool. A further desirable feature of this invention is, that owing to the manner in which the one side of the cover *S* is pivoted to the attachment, very little time is required to change 60 the broaching tool.

I claim:

In a broaching attachment adapted to be secured to the cylinder of a rock drill, the combination of a front head having an open 65 side, a cover pivoted to the front head forming a closure for the open side, cheek plates secured to the front head and the cover spaced to form a rectangular guideway for loosely guiding a broaching tool, said cheek 70 plates having recesses in their inner surfaces near the front end of the guideway to receive a broaching steel collar, said cheek plates also having longitudinal grooves in their inner surfaces extending from the recesses to 75 the rearward ends of the cheek plates for the reception of a broaching tool shank, and I-bolts pivoted to the front head for clamping the cover to the front head.

In testimony whereof I have signed this 80 specification.

CHARLES C. HANSEN.
